PAIR OF NOVELTY GLOVES

Robert Stanton, 140 Geary St., San Francisco, Calif.

Filed July 21, 1960, Ser. No. 61,463

Term of patent 14 years

(Cl. D3—11)

Fig. 1 is a rear view of a pair of novelty gloves showing my new design;

Fig. 2 is a front view thereof; and

Fig. 3 is an elevational view thereof as they appear with the fingers entwined and the thumbs extended to show the design in composite form.

I claim:

The ornamental design for a pair of novelty gloves, as shown and described.
